UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,184,245.

Specification of Letters Patent. Patented May 23, 1916.

Application filed April 7, 1914. Serial No. 830,109.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, and more particularly to that class thereof equipped with a plurality of magazines. It is often desirable to have at hand a considerable number of type or matrices 15 representing additional characters, such as sorts or the like, and to this end is employed a special or supplementary magazine, the escapements of which are controlled by an independent keyboard, and wherein the type 20 or matrices are delivered to the usual belt, which conveys them to the assembling point, and wherein afterward distributing mechanism redelivers them to their respective channels. In many essential respects the 25 general construction is similar to that of the linotype machine shown and described in my Letters Patent of the United States, Nos. 1,115,210; 1,136,534; and 1,136,535.

30 My present improvements contemplate an extension of the same principle, and to that end I equip the machine with a plurality of such supplementary magazines, and in combination therewith employ an arrangement of distributing mechanism to restore 35 the matrices to all the supplementary magazines simultaneously.

The invention is illustrated in connection with that style of machine presented in the Letters Patent of John R. Rogers, No. 40 1,109,872, dated September 8th, 1914, wherein a plurality of main magazines are movably arranged so that any selected one may be brought into operative position at will, but obviously my present improvements are 45 capable of wider application, and might be employed in connection with a single main magazine, or with other arrangements of plural magazines.

The accompanying drawings illustrate a 50 linotype machine having my invention applied thereto, and except as hereinafter set forth, it may be of the class illustrated in Letters Patent of the United States, No. 436,532, to O. Mergenthaler, or in the said 55 Rogers application. While I thus show a

preferred embodiment of my invention, it will be obvious that many changes and variations may be made therein, and in its mode of adaptation, which will still be comprised within its spirit; and that it may be 60 similarly used in connection with typesetting and typecasting machines, or in fact with any kind of typographical machine, whether handling type, dies, or matrices. I therefore desire it to be distinctly understood 65 that I do not limit myself to any specific form or embodiment, except in so far as such limitations are specified in the claims.

Referring to the drawings: Figure 1 is a 70 side elevation of a linotype machine having my improvements embodied therein; Fig. 2 is a rear view partly broken away of the parts shown in Fig. 1; Fig. 2^a shows matrices of the kind stored in the several supplementary magazines; Fig. 3 is a section on the line 2—2 of Fig. 2; and Fig. 4 is a view similar to Fig. 2, presenting a modification.

The main magazines A, A¹, A², (Fig. 1) are carried by a supporting frame A³ which 80 is movably arranged so that by the operation of the handle A⁴ any selected magazine may be brought into operative position at will, and the matrices are restored thereto in the usual manner, through the instrumentality 85 of the distributor rail L, screws L¹, and channel entrance A¹⁰. The parts so far described, may be of the usual construction and mode of operation, and in themselves constitute no part of my present invention. 90

In order to contain the extra or sorts matrices I provide a plurality of supplementary magazines, in the present instance represented by the two superposed magazines B and C, arranged at the side of and 95 in tandem to the main magazines. For the upper magazine B, there is provided a distributor rail M which forms a continuation of the main distributor rail L, the operative or ribbed portions of the two rails being 100 separated by an intermediate blank portion for a purpose later to be described. The matrices are carried along the rail M by screws M¹ which form continuations of the screws L¹ for the main distributor rail. In 105 another sense, therefore, the distributors for the main magazines and the supplemental magazine B may be said to constitute a single distributor for both magazines, although they will hereafter be regarded as two dis- 110

tinct distributers. As the matrices X are released from the distributer rail M they drop into the channel entrance B¹ which conveys them to the magazine B. Similarly, 5 the lower magazine C is provided with a distributer rail N and screws N¹, from which the matrices Y are delivered through the channel entrance C¹. The matrices X and Y, corresponding respectively to the 10 magazines B and C, are illustrated in Fig. 2^a, it being noted that the matrix Y differs from the matrix X in that it is formed in its lower edge with a controlling notch Y¹, the purpose of which will subsequently be 15 apparent.

The regular matrices belonging to the main magazine in position, the matrices X of the magazine B, and the matrices Y of the magazine C, are all delivered to the distributer rail L and are caused to travel along it by the screws L¹, during which operation the regular matrices are restored to the main magazine, while the matrices X and Y pass entirely along the rail and are delivered 20 from the end thereof, all in the manner well understood in the art. The distributer rail M is located in line with the rail L, but with a slight space between their grooved portions, which interval is therefore supplemented by a bridge formed with the upwardly projecting ridge O, located immediately beneath the matrices passing from the rail L. As the matrices X are delivered, 25 their lower edges rest on the ridge and they are engaged by one or more of the screws M¹, whereby they are transferred laterally to the rail M, by which they are restored to their proper channels in the magazine B. However, the matrices Y, due to the registration of their notches Y¹ with the ridge O, 30 are permitted to descend slightly or to a sufficient extent to prevent their engagement with the bar M. They are then moved laterally by the screws M¹ until they pass over 35 the bridge, when they fall into and through the vertical tube P, which is so located and arranged as to deliver the matrices to the inclined shoulders P¹, when they are engaged with the rail N and screws N¹, and 40 are restored through the entrance C¹ to their proper channels in the magazine C.

In Fig. 4 I have shown a modification, 45 wherein the bridge and the notched matrices may be dispensed with. In this case the sorts matrices W of the upper magazine and the sorts matrices V of the lower magazine are both delivered to the upper supplementary rail R, along which they are caused to travel toward the left by the 50 screws R¹. During this operation the matrices W drop from the rail and are restored to the upper magazine, whereas the matrices V pass entirely along it and drop into the tube T, through which they pass, 55 and are then delivered to the inclined

shoulders T¹ and thence to the lower supplementary rail S and screws S¹. It will be noted that these screws rotate in the opposite direction, and consequently the matrices V now travel toward the right, 60 during which operation they are restored to their appropriate channels in the magazine C.

As previously stated, I have shown my invention only in preferred form and by way of example, and in a specific adaptation. However, many modifications and alterations therein, and in its mode of application, will suggest themselves to those skilled in the art, without departure from 65 its scope.

Having thus described my invention, its construction and mode of operation, what I claim and desire to secure by Letters Patent of the United States, is as follows:

1. In a typographical machine, the combination of distributing mechanism, two series of magazines, one of said series having its magazines in constant operative relation to the distributing mechanism, and means whereby one or another of the magazines of the other series may be brought into operative relation thereto.

2. In a typographical machine, the combination of a plurality of magazines movable as a whole to bring one or another into operative position, and a plurality of fixed supplementary magazines, with distributing mechanism to deliver type or matrices to all the supplementary magazines simultaneously.

3. In a typographical machine, the combination of a plurality of magazines movable as a whole to bring one or another into operative position, and a plurality of fixed supplementary magazines, with distributing mechanism to deliver type or matrices simultaneously to all the supplementary magazines and to the main magazine in operative position.

4. In a typographical machine, the combination of a main magazine, a distributer therefor, a plurality of supplementary magazines, and a corresponding plurality of distributers therefor adapted to receive the type or matrices for the supplementary magazines from the main distributer.

5. In a typographical machine, the combination of a main magazine, a distributer therefor, a plurality of supplementary magazines, and a corresponding plurality of distributers therefor, together with means whereby the type or matrices for the supplementary magazines will be delivered from the main distributer to the several supplementary distributers.

6. In a typographical machine, the combination of a main magazine, a distributer therefor, a plurality of supplementary magazines, and a corresponding plurality of dis-

tributers therefor, together with means whereby the type or matrices for the supplementary magazines will be delivered from the main distributer to one or another of the 5 supplementary distributers according to their form.

7. In a typographical machine, the combination of two toothed distributer bars each having a series of character distributing 10 combinations, the said bars being arranged end to end and separated by an untoothed portion, and a selecting bridge underlying the untoothed portion and serving to control the passage of the type or matrices from one 15 bar to the other.

8. In a typographical machine, the combination of a main distributer and two supplementary distributers, one arranged to receive type or matrices directly from the 20 main distributer, and means for conveying type or matrices therefrom to the other supplementary distributer.

9. In a typographical machine, the combination of two toothed distributer bars each 25 having a series of character distributing

combinations, the said bars being arranged end to end and separated by an untoothed portion, a selecting bridge underlying the untoothed portion and serving to carry type or matrices of one form from one bar to the other and to permit type or matrices of another form to become disengaged from both 30 said bars, with a third distributer bar to receive the type or matrices so disengaged.

10. In a typographical machine, the combination with a main distributer to separate matrices according to character and a plurality of supplemental distributers adapted also to separate matrices according to character, of a font distributer arranged in position to receive matrices from the main distributer and separate them according to 35 form or font for delivery to one or another of the supplemental distributers.

In testimony whereof I have affixed my 40 signature in presence of two witnesses.

DAVID S. KENNEDY
